DESIGN FOR A SPANNER WRENCH

Henry M. Miller, Waterbury, Conn., assignor to
Seovill Manufacturing Company, Waterbury,
Conn., a corporation of Connecticut

Application July 16, 1942, Serial No. 107,572

Term of patent 14 years

To all whom it may concern:

Be it known that I, Henry M. Miller, a citizen of the United States, residing at Waterbury, county of New Haven, State of Connecticut, have invented a new, original, and ornamental Design for Spanner Wrenches, of which the following is a specification, reference being had to the accompanying drawing, forming part thereof.

Fig. 1 is a perspective view of a spanner wrench embodying my new design.

Fig. 2 is a front elevational view of the spanner wrench.

Fig. 3 is a longitudinal view looking from the top of Fig. 2.

Fig. 4 is an end elevational view from the left of Fig. 2.

Fig. 5 is a cross-section taken along line 5—5 of Fig. 2, and

Fig. 6 is a similar view taken along line 6—6 of Fig. 2.

I claim.

The ornamental design for a spanner wrench, substantially as shown.

HENRY M. MILLER.
